UNITED STATES PATENT OFFICE.

FRANK C. HALL, OF PHILADELPHIA, PENNSYLVANIA, ASSIGNOR TO WILLIAM C. STEVENSON, OF SAME PLACE.

GRINDING-MILL.

SPECIFICATION forming part of Letters Patent No. 406,522, dated July 9, 1889.

Application filed November 1, 1888. Serial No. 289,760. (No model.)

To all whom it may concern:

Be it known that I, FRANK C. HALL, of Philadelphia, in the county of Philadelphia and State of Pennsylvania, have invented a new 5 and useful Improvement in Grinding-Mills; and I do hereby declare that the following is a full, clear, and exact description of the same.

My invention is designed particularly for grinding paint; but I do not limit myself to 10 its use for grinding this particular material, as it may be used for the grinding of other materials, if found desirable.

The invention is particularly useful in the grinding of paint, by reason of the fact that I 15 make provision in one mill for a series of grinding-surfaces, so that the capacity of the mill is equal to as great a number of single mills as there are grinding-surfaces in my improved mill. By so combining a number of 20 grinding-surfaces I secure compactness and economy of space. Further than this I provide a single hopper, including all the openings leading to the series of grinding-surfaces, by means of which, when it is desired to grind 25 a paint of one color in all the mills, the material may be poured into the hopper common to all, and it will thus find its way to each grinding-surface. When it is desired, however, to 30 grind different colors at the same time, I provide supplemental hoppers, which are placed removably within the openings in the bottom of the outer hopper leading to the independent 35 grinding-surfaces, whereby each grinding-surface may be utilized to grind different colors, the material being fed to each grinding-surface through its own hopper. My mill is thus 40 capable of two different kinds of use, namely: first, the simultaneous grinding of several colors, and, secondly, the grinding of one color upon all of the grinding-surfaces of the mill. The supplemental hoppers are removable, and 45 when removed the mill has a larger capacity for grinding paints of one color, all the grinding-surfaces operating thereon. I have found by practical use that a mill of this form, having 50 multiple grinding-surfaces and a hopper common to all, operates to better advantage than a mill with a single hopper and a single grinding-surface—that is to say, the mill with 55 the multiple grinding-surfaces and the single

hopper will perform more work in a given amount of time than a mill of the same size of the old form. The adhesive nature of the material operated upon by these mills causes it to act in the process of grinding in a peculiar manner, and it appears that the single hopper allows the paint to feed more freely down to the grinding-surfaces, while the smaller grinding-surfaces act more efficiently than a single grinding-surface would of the 60 same extent as an aggregate of the smaller grinding-surface.

My invention consists, therefore, of a series of grinding-surfaces having an outer hopper common to all, with openings in the bottom 65 of said hopper leading to each grinding-surface and a removable supplemental hopper for each opening, whereby the surfaces may be used to grind one material with the outer hopper common to all, or to grind different 70 materials by the use of the supplemental hoppers.

In the drawings, Figure 1 is a front elevation of my improved mill. Fig. 2 is a section through the outer hopper, showing one of the 75 supplemental hoppers in place.

In these figures a hopper A is shown supported upon four posts B, and this hopper is provided with four openings in its bottom plate C, which lead to the grinding and crushing surfaces of four grinding-mills which are placed directly beneath the hopper. These mills may be of the form shown in Letters Patent granted to me January 22, 1889, No. 396,559, or of any desired form. Instead of 80 four, two or more may be used. In combining the series of mills in one apparatus I provide for driving them simultaneously through the centrally-located shaft a, which carries upon its lower end a crown-wheel b, which receives motion through a bevel-gear d, fixed to the inner end of the shaft e, upon which is placed the driving-pulley f, which is in connection by belting with a suitable source of power. The spindles of the grinding-mills 85 are provided with gears which mesh into a central driving-gear on the upper end of the shaft a, so that from this central driving-gear all the mills of the series may be driven. It will be understood that in case a greater or 90

100

less number of mills are used a modification of this driving mechanism may be provided. In order to disconnect at will any one or more of the mills from the driving mechanism, I provide a clutch *g*, (shown in detail,) by means of which the spindle or spindles may be thrown out of engagement with the driving-power, and the mill thus remain idle. These clutches are operated each by its own handle *h*. Each mill is provided with a scraper *I*, which bears upon the periphery of the runner, and the movement of the runner cleans it from the material adhering thereto, which falls into the discharge-chute and from thence into a suitable receptacle. I provide for the adjustment of the spindles by seating their lower ends in a bearing-block which is held in a pocket formed in a hanger *k*, pivoted at one end and connected at the other end to the screw-threaded end of a hand-wheel *l*, which has its bearings in one of the lower cross-braces of the machine. By manipulating this hand-wheel a proper adjustment of the spindle may be secured. It will be understood that each spindle has this adjustment. It will be seen from an inspection of the drawings, particularly Fig. 2, that each of the series of grinding-surfaces has an independent opening leading thereto, with the outer hopper *A* common to all the openings, so that when it is desired to grind the same kind of mate-

rial in all the mills the said material is simply poured into the hopper *A*, and thus finds its way to the grinding-surface of each mill. When, however, it is desired to grind different kinds of material in each mill, the supplemental hoppers are fitted to the openings leading to the grinding-surfaces, and thus each grinding-surface is provided with an independent hopper.

I claim as my invention—

1. In combination with a series of independent grinding-surfaces, an outer hopper with openings in the bottom thereof leading to each grinding-surface, and a supplemental removable hopper for each opening, whereby the grinding-surfaces may be utilized to grind material of one kind or color or materials of different kind or color, substantially as described.
2. In a grinding-mill, a series of independent grinding-surfaces combined with a single outer hopper and openings within said hopper, one leading to each grinding-surface, and operating mechanism for the grinding-surfaces, substantially as described.

In testimony whereof I have signed my name to this specification in the presence of two subscribing witnesses.

FRANK C. HALL.
